G. H. STALLMAN.
ROTARY PUMP OR COMPRESSOR.
APPLICATION FILED DEC. 17, 1920.

1,418,741.

Patented June 6, 1922.

UNITED STATES PATENT OFFICE.

GRANVILLE H. STALLMAN, OF CHICAGO, ILLINOIS.

ROTARY PUMP OR COMPRESSOR.

1,418,741.

Specification of Letters Patent. Patented June 6, 1922.

Application filed December 17, 1920. Serial No. 431,339.

To all whom it may concern:

Be it known that I, GRANVILLE H. STALLMAN, a citizen of the United States, residing at Chicago, in the county of Cook and State 5 of Illinois, have invented certain new and useful Improvements in Rotary Pumps or Compressors, of which the following is a specification.

This invention relates to improvements in 10 a rotary pump or compressor, particularly adapted though not necessarily limited in its use for moving or handling fluids or plastic materials, and one of the objects of the invention is to provide an improved apparatus of this character which will be simple in construction, effective and efficient in operation, and economical in power.

A further object is to provide an improved apparatus of this character embodying two 20 co-operating and inter-meshing rotary elements so shaped as to alternately form closed pockets in the elements and in which pockets portions of the material are first trapped, then subjected to a gradually increasing 25 pressure while in the pocket and finally ejected from the respective pockets as the pockets assume predetermined positions with relation to a discharge outlet passage.

To the attainment of these ends and the 30 accomplishment of other new and useful objects as will appear, the invention consists in the features of novelty in substantially the construction, combination and arrangement of the several parts hereinafter more 35 fully described and claimed and shown in the accompanying drawing illustrating this invention, and in which—

Figure 1 is a vertical sectional view as taken on line —1— Figure 2, of a machine 40 adapted to pump compressible materials.

Figure 2 is a horizontal view as taken on line 2—2, Figure 1.

Figure 3 is a view of the machine for handling incompressible materials.

In the specification and claims the invention will be described in connection with the moving or compressing of a fluid, but it is to be understood that this invention and the same principle thereof is well adapted for 45 use in moving or handling plastic materials, as for instance the apparatus may be effectively employed as a stuffing machine, and it is therefore to be understood that the term fluid as used throughout the specification 50 and claims, for the sake of uniformity, is not to be construed to be a term of limita-

tion as to the use or adaptability of the apparatus.

Referring more specifically to the drawing the numeral 10 designates a fluid receiving casing supported in any suitable manner such as by means of a support 11, and is provided with a fluid inlet opening 12.

This casing 10, may be of any desired size 65 and configuration.

Rotatably mounted within the casing are elements 13—14, and these elements are respectively provided with a series of circumferentially spaced teeth or projections 70 15—16, and the elements are so arranged that these teeth or projections will mesh. The teeth or projections are formed preferably with substantially circular shaped extremities 17, the throats 18, of the teeth being reduced so as to form pockets or chambers 19, intermediate adjacent teeth or projections and at the base thereof. The ends 17, of the teeth or projections 16, are of a size and configuration so as to conform to the 80 contour of the pockets 19, so that when they enter the respective pockets they will fill the pockets for a purpose to be hereinafter set forth.

The elements are respectively mounted 85 for rotation upon hollow shafts 20—21, which project through one end 22, of the casing 10, suitable packing 23, being provided to prevent the escape of fluid. These hollow shafts 20—21 are preferably connected at their free extremities by means of a manifold 24, having a common discharge outlet 25, suitable couplings 26, being employed in connecting the manifold with the shafts. These shafts 20—21 project into the 90 respective elements 13—14 for any desired distance but preferably terminate short of one end of the respective elements so that a portion of the elements will form closures 27—28 for the ends of the shafts, and the 100 shafts are respectively provided with openings 29—30 extending radially therethrough and in directions lengthwise of the shaft.

The elements 13—14 may be of any desired length and are arranged within a 105 chamber 29^a formed within the casing 10, by means of a wall 31, which co-operates with the end 22, of the casing. The outer wall of the casing is projected beyond the wall 31, and is closed by another wall 32, 110 to form a chamber 33. The elements 13—14 are respectively provided with trunnions 34

- 35, which pass through the wall 31 and are journaled in suitable bearings 36—37, arranged within the chamber 33, and connected with these trunions 34—35, are in 5 termeshing gears 38—39, which are given rotation through the medium of a shaft 40, from any suitable source of power. The pinions when thus rotated will impart a rotary movement to the elements 13—14. 10 A suitable packing 41, may be provided for the shaft 40.

Each of the pockets 19, is provided with a discharge opening 42, leading therefrom and as the elements 13—14 are rotated the 15 discharge openings 42, from the pockets will be successively brought into and out of engagement with the respective openings 29—30, in the shafts 20, 21 to establish communication between the pocket and the discharge outlet 25.

- In use the fluid is supplied to the casing 10, through the inlet opening 12, and as the elements 13—14 are rotated the teeth or projections 15—16 on the respective elements 25 13—14, will be successively projected into the pockets 19, of the other element with the result that these projections or teeth 15—16, will first close the pockets to trap portions of the fluid in the pockets and a 30 continued rotation of the elements will cause a gradually increasing pressure to be exerted upon the trapped fluid in the pocket while the projection on one element is entering the pocket in the other element. This 35 gradually increasing pressure which has thus been exerted upon the trapped fluid will continue until the respective elements 13—14 are moved to a position that the discharge outlet 42, thereof is brought into 40 register or in communication with the discharge outlet 25, through the medium of the respective openings 29—30, in the shafts 20—21, at which time the tooth or projection will continue to enter the pocket and 45 fill the pocket while at the same time the trapped fluid in the pocket will be ejected through the discharge outlet 42.

It will thus be seen that as the elements 13—14 are rotated the operation above 50 described will continue and the fluid will be compressed and ejected alternately from the pockets in the two elements.

Obviously the various parts of this apparatus will be correspondingly arranged 55 according to the material which is being handled thereby, so as to compensate the different natures of the material.

In Figure 3, the ports 29^a and 30^a in the respective pipes 20 and 21 are enlarged so 60 as to avoid compression in the pockets 19 before the material is discharged therefrom.

While the preferred form of the invention has been herein shown and described it is to be understood that various changes may 65 be made in the details of construction and

in the combination and arrangement of the several parts, within the scope of the claims, without departing from the spirit of this invention.

What is claimed as new is:

1. An apparatus of the character described embodying a fluid receiving casing having an inlet and a discharge outlet, a rotary element in the casing provided with recesses forming chambers, said chambers 75 each having a discharge outlet movable into and out of communication with the first said discharge outlet, and means co-operating with the said chambers for closing them, the said means operating to compress the 80 fluid within the chambers when the discharge outlet thereof is out of communication with the first said outlet, and also operating to force the fluid from the chamber when the said outlets are brought into 85 communication.

2. An apparatus of the character described embodying a casing, having an inlet and a discharge outlet for the fluid to be operated upon, a rotary element in the 90 casing provided with independent chambers or spaces for receiving the fluid, said chambers each having a discharge outlet, the last recited outlets being movable into and out of communication with the first recited outlet as the element is rotated, and means operating to first successively close the chambers to trap the fluid therein and then compress the fluid within the chamber when the outlet therefrom is closed, the 95 said means moving with the chamber to eject the fluid therefrom when the outlet of the chamber moves into communication with the first recited outlet.

3. An apparatus of the character described 105 embodying a casing, having an inlet and a discharge outlet for the fluid to be operated upon, a rotary element in the casing provided with independent chambers or spaces 110 for receiving the fluid, said chambers each having a discharge outlet, the last recited outlets being movable into and out of communication with the first recited outlet as the element is rotated, and means operating to first successively close the chambers to 115 trap the fluid therein and then compress the fluid within the chamber when the outlet therefrom is closed, the said means moving with the chamber to eject the fluid therefrom, when the outlet of the chamber moves into communication with the first recited outlet, the said means embodying a rotary 120 element having spaced peripheral teeth or projections conforming to the contour of the chambers and adapted to enter and fill 125 the said chambers.

4. An apparatus of the character described embodying a casing, having an inlet and a discharge outlet for the fluid to be operated upon, a rotary element in the casing pro- 130

- vided with independent chambers or spaces for receiving the fluid, said chambers each having a discharge outlet, the last recited outlets being movable into and out of communication with the first recited outlet as the element is rotated, means operating to first successively close the chambers to trap the fluid therein and then compress the fluid within the chamber when the outlet therefrom is closed, the said means moving with the chamber to eject the fluid therefrom when the outlet of the chamber moves into communication with the first recited outlet, the said means embodying a rotary element having spaced peripheral teeth or projections conforming to the contour of the chambers and adapted to enter and fill the said chambers, means for rotating one of the elements and means operatively connecting the said elements.
5. An apparatus of the character described embodying a fluid receiving casing having an inlet and a discharge outlet, complementary rotatable elements each being provided with circumferentially spaced projections to form chambers therebetween, each of the chambers having a discharge outlet opening movable into and out of communication with the first recited discharge outlet, and means for causing rotation of the elements, the said projections on each of the elements co-operating with the chambers on the other element to first close the respective chambers to trap the fluid therein, then compress the fluid during that portion of the operation of the respective elements that the discharge outlet from the respective chambers is out of communication with the first recited outlet, and then discharge the fluid from the respective chambers when the respective outlets move into communication with the first recited outlet.
6. An apparatus of the character described embodying a fluid receiving casing having an inlet and a discharge outlet, complementary rotatable elements each being provided with circumferentially spaced projections to form chambers therebetween, each of the chambers having a discharge outlet opening movable into and out of communication with the first recited discharge outlet, and means for causing rotation of the elements, the said projections on each of the elements co-operating with the chambers on the other element to first close the respective chambers to trap the fluid therein, then compress the fluid during that portion of the operation of the respective elements that the discharge outlet from the respective chambers is out of communication with the first recited outlet, and then discharge the fluid from the respective chambers when the respective outlets move into communication with the first recited outlet, the first recited discharge outlet embodying hollow shafts individual to the elements and upon which the elements rotate, there being an opening through each of the shafts and extending lengthwise thereof.
7. An apparatus of the character described embodying a fluid receiving casing having an inlet and a discharge outlet, complementary rotatable elements each being provided with circumferentially spaced projections to form chambers therebetween, each of the chambers having a discharge outlet opening movable into and out of communication with the first recited discharge outlet, and means for causing rotation of the elements, the said projections on each of the elements co-operating with the chambers on the other element to first close the respective chambers to trap the fluid therein, then compress the fluid during that portion of the operation of the respective elements that the discharge outlet from the respective chambers is out of communication with the first recited outlet, and then discharge the fluid from the respective chambers when the respective outlets move into communication with the first recited outlet, the first recited discharge outlet embodying hollow shafts individual to the elements and upon which the elements rotate, there being an opening through each of the shafts and extending lengthwise thereof.
8. An apparatus of the character described embodying a fluid receiving casing having an inlet and a discharge outlet, a pair of toothed rotary elements in the casing, said elements meshing with each other, the spaces between adjacent teeth of each of the members forming fluid pockets, there being a discharge outlet leading from each pocket and movable into and out of communication with the first recited outlet, the teeth of each element co-operating with the pockets of the other element to first close the pockets to trap the fluid therein, then compress the fluid when the discharge outlets of the respective pockets are closed, and then eject the fluid from the pocket when the outlet therefrom is in communication with the first recited discharge outlet, and means for rotating the elements.
9. An apparatus of the character described embodying a fluid receiving casing having an inlet and an outlet, a pair of toothed meshing rotary elements in the casing, portion of each element between adjacent teeth being shaped to form fluid pockets, there being a discharge outlet from each pocket movable into and out of communication with the first recited outlet, said teeth of each member being shaped to conform to the con-

- tour of and fill the respective pockets of the other member whereby when the members are rotated the teeth will first close the respective pockets to trap the fluid therein, then exert 5 a gradually increasing pressure upon the fluid as the tooth enters the pocket during the period that the outlet from the pocket is out of communication with the first recited outlet, and then eject the fluid from 10 the pocket when the outlet therefrom is in communication with the first recited outlet, and when the tooth completely fills the pocket.
10. An apparatus of the character de- 15 scribed embodying a fluid receiving casing having an inlet, a toothed like rotatable element having pockets intermediate the teeth, said pockets each having a discharge outlet, means co-operating with the pockets for clos- 20 ing them to trap liquid therein and exert a gradually increasing pressure upon the liquid, and means adjacent the axis of rotation of the element whereby the said discharge outlets from the pockets are closed 25 during a predetermined portion of the rotation of the element and are opened during another predetermined portion of the rotation of the element to permit the discharge of the fluid from the pocket.
- 30 11. An apparatus of the character de- scribed embodying a fluid receiving casing having an inlet, a rotatable element having pockets intermediate the teeth, said pockets each having a discharge outlet, means co- 35 operating with the pockets for closing them to trap liquid therein and exert a gradually increasing pressure upon the liquid, and means adjacent the axis of rotation of the element whereby the said discharge outlets 40 from the pockets are closed during a predetermined portion of the rotation of the element and are opened during another predetermined portion of the rotation of the element to permit the discharge of the fluid from the pocket, the second recited means 45 embodying a passageway for receiving the fluid from the discharge outlets of the pockets.
12. An apparatus of the character de- 50 scribed embodying a casing for receiving fluid, and having an inlet, a pair of toothed like rotatable intermeshing elements each
- having pockets intermediate adjacent teeth, each of the pockets having a discharge outlet therefrom, the teeth of each element co- 55 operating with the pockets of the other element to close them to trap fluid therein and exert a gradually increasing pressure upon the fluid, and means adjacent the axes of rotation of the elements whereby said dis- 60 charge outlets from the pockets will be closed during a predetermined portion of the rotation of each element and will be open during another predetermined portion of rotation of each element to permit the discharge 65 of the fluid from the respective pockets.
13. An apparatus of the character de- scribed embodying a casing for receiving fluid, and having an inlet, a pair of toothed like rotatable intermeshing elements each 70 having pockets intermediate adjacent teeth, each of the pockets having a discharge outlet therefrom, the teeth of each element co- operating with the pockets of the other element to close them to trap fluid therein and 75 exert a gradually increasing pressure upon the fluid, and means adjacent the axes of rotation of the elements whereby said dis- charge outlets from the pockets will be closed during a predetermined portion of the ro- 80 tation of each element and will be open during another predetermined portion of rotation of each element to permit the discharge of the fluid from the respective pockets, the 85 said means embodying passageways for receiving the fluid alternately from the discharge outlets of the pockets, the said passageways having a common delivery outlet.
14. An apparatus of the character de- scribed embodying a fluid receiving casing 90 having an inlet and a discharge outlet, a ro- tary element in the casing provided with re- cesses forming chambers, said chambers each having a discharge outlet movable into and out of communication with the first said dis- charge outlet, and means co-operating with the said chambers for closing them, the said means operating to force the liquid from the chamber when the outlets are brought into communication.
- In testimony whereof I have signed my name to this specification on this 11th day of December, A. D. 1920.
- GRANVILLE H. STALLMAN.
